UNITED STATES PATENT OFFICE.

JOHN S. FLANDERS, OF STURGIS, MICHIGAN.

TYPE-WRITER ATTACHMENT.

SPECIFICATION forming part of Letters Patent No. 700,755, dated May 27, 1902.

Application filed December 11, 1901. Serial No. 85,454. (No model.)

To all whom it may concern:

Be it known that I, JOHN S. FLANDERS, a citizen of the United States, residing at Sturgis, in the county of St. Joseph and State of Michigan, have invented a new and useful Improvement 5 in Type-Writer Attachments, of which the following is a specification.

My invention relates to type-writer attachments, of which the object is to provide a 10 mechanism operated by the foot of the operator and adapted to be connected with the shift-key of a type-writer, obviating the use of the hand thereon, and, further, to provide a cheap and simple means of operating the 15 shift-key of a type-writer, easily connected thereto at any convenient point and readily detached therefrom, dispensing with the use of a spring or other additional device on said shift-key. I attain these objects by the mechanism 20 illustrated in the accompanying drawings, forming a part of this specification.

Figure 1 is a side elevation of a type-writing machine with my improvement attached. Fig. 2 is a perspective view of a portion of 25 my improvement resting on the floor. Fig. 3 is a cross-section elevation of Fig. 1. Fig. 4 is a detail view of the clamp attachment of my improvement. Fig. 5 is a detail view of the bolt-and-pin attachment.

Similar numerals refer to similar parts in 30 each of the several drawings.

Numerals 1 designates the frame of a type-writing machine. 3 4 5 are the connections between the shift-key 2 and the carriage.

The attachment consists of a base 9, adapted 35 to rest on the floor and formed, preferably, of plate metal. A suitable portion of one end 10 is turned up at a required angle thereto, the upper end of which is bent at a right angle 40 backward, forming a stop 15 to detain a foot-lever 8. Side pieces 16 of the upright 10 are clipped out and turned backward and over the stop 15, forming a brace for the same. One side of a triangular piece 11 of the 45 upright 10, with the rectangular portion 14 of the base 9 integral therewith and bent at right angles thereto, is cut out and bent forward in line with the axis of said base, forming a supporting-bracket 11 for said upright 50 10 and may be secured to the floor at 14'. A foot-lever 8 is attached to the base by a hinge 13 and kept in position up against the stop 15 by a spring 12, resting on the base 9. A flexible metal clamp 6 is placed over the shift- 55 key 2, on which it rests squarely and is formed

to clasp the same firmly, as shown in Fig. 4, and thus retain its position, and is connected by a wire 7 or other flexible material, attached to the lower end through an orifice therein, with a hook on the upper end of a screw-threaded pin 18, inserted in a screw-threaded recess cut in a headed bolt 19, which projects through the orifice 20 in the foot-lever 8. The tension of the wire 7 is readily adjusted by the manipulation of the pin 18. 65 The spring 12 raises the lever 8 when relieved of foot-pressure.

The device may be placed in any convenient position on the floor beneath the type-writer machine, so as to permit the placing 70 of the clamp 6 on the shift-key, and being flat can be readily inserted without affecting the movement of adjacent keys. The formation and flexibility of the said clamp enable it to clasp firmly the shift-key, and thus 75 secure a permanency of position and convenience of the operator.

The improved construction of my device also eliminates the interposition of a spring or other means under the shift-key to cause 80 the retraction of the foot-lever and renders my improvement a complete self-contained device readily attached and removed.

The foregoing description and accompanying drawings plainly show that my improvement 85 obviates the necessity of the use of the operator's hand to operate the shift-key.

Having fully described my invention, what I claim as new, and desire to secure by Letters Patent, is—

A type-writer attachment comprising a foot-power adapted to be placed on the floor in any convenient position, composed of a base, an upright portion, side pieces and a stop, formed thereon, a triangular bracket and rectangular integral base, a spring, a foot-lever hinged to said base, a hooked, screw-threaded pin, operating in a screw-threaded recessed and headed bolt, in combination with a flexible metallic clamp, adapted to clasp a shift-key, and a flexible connection between said clamp and said pin, all substantially as described and for the purpose set forth.

In testimony whereof I have affixed my signature in presence of two witnesses.

JOHN S. FLANDERS.
